UNITED STATES PATENT OFFICE.

RAND S. BAILEY, OF MONTCLAIR, NEW JERSEY, ASSIGNOR TO AMERICAN TELEPHONE AND TELEGRAPH COMPANY, A CORPORATION OF NEW YORK.

TELEPHONE SYSTEM.

Application filed October 11, 1922. Serial No. 593,850.

This invention relates to telephone systems and more particularly to systems wherein subscribers' lines terminate at a plurality of operators' positions so that a call emanating from such a subscriber's station may be attended to by any one of a plurality of operators.

It is an object of this invention to improve the means for excluding an operator from access to a subscriber's line when a call on said line is being handled by another operator.

Another object of this invention is to inform an operator when she has attempted to answer a call over a subscriber's line, that the call is already being attended to by another operator.

The foregoing objects are obtained in accordance with one feature of this invention by the provision, in a cord circuit, of a sleeve relay which is controlled through a normally closed contact of a slow-to-operate answering supervisory relay, and which operates when the cord is connected with a busy line, thereby preventing the connection of the operator's telephone set with the cord circuit.

Another feature of this invention is the provision of a circuit arrangement such that the battery supply is disconnected from the answering plug of the cord circuit when such cord is connected with a busy line thereby preventing the operation of the supervisory relay.

A still further feature is the provision of a circuit arrangement whereby signals are given at both the answering and calling ends of the cord circuit when the cord is connected to a busy line.

The manner in which the foregoing objects and features are effected will be readily understood from the following detailed description taken in reference to the accompanying drawings in which Figure 1 shows one embodiment of the invention and discloses a calling subscriber's station, a four-party line and a cord circuit for interconnecting the calling station with the four-party line. Fig. 2 shows another embodiment of the invention and also discloses a calling subscriber's station, a four-party line and an interconnecting cord circuit.

In the following detailed description, it will be assumed that a subscriber at the station on line A is the calling subscriber and

one of the parties on the four-party line B is the called subscriber.

Upon initiating a call, the subscriber at station A removes the receiver from the switchhook and establishes an energizing circuit for line relay 3 which may be traced from grounded battery through the right-hand winding of relay 3, inner armature and back contact of cut-off relay 4, line conductor 5, over the subscriber's line loop, line conductor 6, outer armature and back contact of cut-off relay 4, and thence to ground, through the left-hand winding of line relay 3. Relay 3, in operating, completes a circuit extending from grounded battery through the armature and front contact of relay 3, conductor 7, and thence to ground through the filaments of the line lamps 8, 9 and 10, which lamps are located in front of different operators at a central office, any one of which operators may answer the call. The lamps are illuminated in the circuit just traced thereby notifying all the operators that a call is awaiting attention.

It will be assumed at this time that the operator at the position at which lamp 10 is located, is free to handle the incoming call. This operator, therefore, inserts the plug 11 associated with the cord circuit C into jack 12 located at her position and associated with the calling subscriber's line.

Upon the insertion of plug 11 into jack 12, an energizing circuit for slow-operating supervisory relay 13 is established which is traced from grounded battery through the lowermost armature and back contact of relay 14, lower left-hand winding of repeating coil 15, winding of relay 13, ring contacts of plug 11 and jack 12, over the subscriber's line loop, tip contacts of jack 12 and plug 11, upper left-hand winding of repeating coil 15, and upper armature and back contact of relay 14 to ground. Relay 13 thereupon operates and disconnects the discriminating test relay 16 from the sleeve of the cord circuit and substitutes therefor the regular sleeve relay 17. Relay 17 thereupon operates in the circuit just established extending from grounded battery through the winding of relay 17, conductor 18, armature and front contact of relay 13, sleeve contacts of plug 11 and jack 12, sleeve conductor 19 and thence to ground through the winding of cut-off relay 4. Relay 4 ener-

gizes in this circuit and disconnects the line relay 3 from the line conductors leading to the subscriber's station A, whereupon relay 3 releases its armature thereby extinguishing the multiple line lamp signals 8, 9 and 10. Sleeve relay 17 at its lowermost and uppermost armatures and front contacts connects the operator's telephone set (not shown but designated on the drawing by the letters "OT") to the cord circuit. At its inner lower armature and front contact, relay 17 connects the position register 20 to the cord circuit whereupon the position register is operated over a circuit extending from 15 grounded battery through the operating windings of the register 20, conductor 22, inner lower armature and front contact of relay 17, conductor 23, and thence to ground through the inner lower armature and back 20 contact of relay 21.

It is thought unnecessary in this description to go into detail as to the object and operation of the position register 20, as this apparatus does not enter into the invention. 25 The operator then ascertains from the calling subscriber the nature of the call and upon learning that a subscriber on line B is desired inserts the calling plug 24 associated with cord circuit C into the jack 25 30 associated with the four-party line B.

When plug 24 is inserted in jack 25, an energizing circuit is established for relay 21, extending from grounded battery, through the winding of relay 21, sleeve conductor 26, sleeve contacts of plug 24 and jack 25 to ground through the winding of cut-off relay 75. Relay 21 upon energizing disconnects at its lowermost and uppermost armatures and back contacts, the operator's 40 telephone set from the talking conductors of the cord circuit and at its inner lower armature and back contact disconnects the position register 20 from the cord circuit. At its inner upper armature and front contact, relay 21 completes a circuit for the 45 pick-up interrupter X which may be traced from grounded battery through the interrupter X, when the brush of such interrupter rests on a live segment thereof, conductor 27, break contacts of relay 28, conductor 29, outer armature and back contact of relay 32, conductor 30, winding of relay 28, conductor 31, and thence to ground through the inner upper armature and front contact of relay 21. Relay 28 energizes in 50 this circuit and establishes a locking circuit for itself which may be traced from grounded battery, through the inner armature and front contact of relay 28, conductor 29, outer armature and back contact of relay 32, conductor 30, winding of relay 28 and conductor 31, to ground, through the inner upper armature and front contact of relay 21. Relay 28 at its outer armature 55 and front contact, interconnects the con-

ductors 44 and 60 for ringing purposes to be hereinafter described.

Relay 21, in operating, as previously mentioned, closes its make contact to ground, thereby establishing a circuit extending 70 from grounded battery through the winding of relay 33, conductor 34, armatures and back contacts of relays 32 and 35, conductor 36, make contact of relay 21, and thence to ground, through the inner upper armature 75 of relay 21. Relay 33 energizes in the circuit just traced, thereby connecting the conductors of the subscriber's line B with the conductors 48 and 49 which are associated with the party ringing keys M⁹⁹, J⁹⁸, R⁹⁷ 80 and W⁹⁶.

The called line B is now conductively associated with the conductors of the cord circuit in such a manner as to permit the transmission of signaling current over the 85 called line by the operation of any one of the keys M⁹⁹, J⁹⁸, R⁹⁷, or W⁹⁶.

The system disclosed in the drawing is designed for four-party semi-selective signaling and the manner in which the called 90 parties are signalled may be readily understood from the following description.

Assuming that the party W on line B is desired, the operator will actuate the ringing key W⁹⁶ and in so doing grounds the 95 tip conductor of the cord circuit at the right-hand contacts of key W⁹⁶. The key W⁹⁶ at its left-hand contacts 45 establishes a circuit extending from the one-ring signaling source associated with the interrupter 100 Z, over conductor 64, left-hand armature and back contact of relay 41, conductor 42, uppermost armature and back contact of relay 14, conductor 43, winding of relay 35, conductor 44, contacts 45 of key W⁹⁶, conductor 46, left-hand normal contacts of key 105 R⁹⁷, conductor 47, right-hand normal contacts of key J⁹⁸, conductors 37 and 48, lowermost armature and front contact of relay 33, ring contacts of plug 24 and jack 25, 110 ring conductor of the line B, and thence to ground, through the operating windings of the bells located at the stations W and R. It is to be noted here that the ringing current source at Z transmits a one-ring signal 115 current and the party at R is supposed to heed only a two-ring signal so that this party will ignore the ringing of the bell at this time, whereas the party at W will recognize the one-ring signal and proceed to answer 120 the call.

If party R is the called-for subscriber, the operator actuates key R⁹⁷ and, in so doing, places ground on the right-hand contact 125 of key R⁹⁷, thereby establishing an energizing circuit for relay 41, which may be traced from grounded battery through the inner armature and front contact of relay 28, conductor 29, outer armature and back contact of relay 32, conductor 30, winding 130

of relay 41, conductors 61 and 62, and thence to ground, through the right-hand contacts 63 of key R⁹⁷. Relay 41 thereupon energizes and disconnects the one-ring signaling source at Z from conductor 44 and substitutes therefor the two-ring signaling source at Y which transmits ringing current over a circuit extending from the grounded source at Y, conductor 40, right and left-hand armatures and front contacts of relay 41, conductor 42, upper armature and back contact of relay 14, conductor 43, winding of relay 35, conductors 44 and 66, outer right-hand armature and front contact of relay 28, conductors 65 and 60, contacts 67 of key R⁹⁷, conductor 47, right-hand normal contacts of key J⁹⁸, conductors 37 and 48, lowermost armature and front contact of relay 33, ring contacts of plug 24 and jack 25, ring conductor of the line B, through the operating windings of the bells at stations W and R to ground. A two-ring signal, therefore, actuates the bells at both stations W and R. The party at W ignores the two-ring signal whereas the party at R heeds the signal and proceeds to answer the call.

It is to be noted from the foregoing description that ringing current is transmitted to the station W over the ring conductor from the one-ring signaling source Z, whereas as the party R is signalled over the ring conductor from the two-ring signaling source Y.

Had party J been the called subscriber, the operator would actuate the key J⁹⁸ and in so doing put ground on the ring conductor of the cord circuit. It is to be understood that all of the keys and the apparatus depending on the actuation thereof are in normal condition. Relay 41 is then in normal condition and a circuit may be traced from the one-ring signaling source at Z over conductor 64, left-hand armature and back contact of relay 41, conductor 42 uppermost armature and back contact of relay 14, conductor 43, winding of relay 35, conductors 44 and 66, upper armature and front contact of relay 28, conductors 65 and 60, contacts 68 of key J⁹⁸, conductor 69, left-hand normal contacts of key M⁹⁹, right-hand normal contacts of key W⁹⁶, conductors 38 and 49, uppermost armature and front contact of relay 33, tip contacts of plug 24 and jack 25, tip conductor of the line B and then to ground through the operating windings of the bells at stations J and M. The subscriber at M responds only to a two-ring signal and on hearing the one-ring signal ignores it, whereas the party J recognizes the one-ring signal and proceeds to answer the call.

In order to signal the party at M, the operator actuates key M⁹⁹ thereby establishing an energizing circuit for relay 41 which circuit, in view of the description in con-

nection with the operation of key J⁹⁸, is obvious. Relay 41, as before, substitutes the two-ring signaling source at Y for the one-ring source at Z whereupon signaling current from the two-ring source Y is transmitted over the tip conductor of the cord circuit to actuate the bells at stations M and J. In this case, the party J ignores the two-ring signal while the party M responds to it.

In connection with the operation of keys M⁹⁹ and J⁹⁸, it will be noted that the party M is signalled over the tip conductors from the two-ring signaling source Y, whereas the party J is signalled over the tip conductor from the one-ring signaling source Z.

In the foregoing description of the ringing operation, it will be observed that relay 35 was included in each of the ringing current circuits but does not operate during the ringing period.

Having described the manner in which the four parties W, J, R and M are signalled, it will only be necessary to describe the effect on the cord circuit apparatus when a subscriber at one of the stations responds to a signal as the operations in connection with the other stations are identical.

Let it be assumed that the party W responds by removing the receiver from the switchhook. In so doing, the current in the circuit including relay 35 is increased to such an extent as to cause the operation of this relay. Relay 35, in operating, removes the shunt path around the winding of relay 32, whereupon relay 32 operates in series with relay 33. Relay 32, at its inner armature and front contact, connects battery directly to its winding, thereby shunting relay 33 which thereupon releases. Relay 33, in retracting its armatures disconnects the ringing current source from the talking conductors of the cord circuit and renders the talking conductors conductively continuous. The party at station A is now free to converse with the party W on line B.

Upon completion of the conversation, the calling subscriber restores the receiver to the switchhook at station A and thereby interrupts the circuit for supervisory relay 13 which deenergizes and releases its armature thereby causing the deenergization of relay 17. Relay 17, at its inner upper armature and back contact, establishes a circuit for supervisory lamp 55. The circuit for lamp 55 is traced from grounded battery, through the filament of lamp 55, inner upper armature and back contact of relay 17, conductor 59, inner lower armature and front contact of relay 21 to ground. When the called subscriber replaces the receiver on the switchhook, the circuit for supervisory relay 58 is interrupted. Relay 58 thereupon releases and establishes a circuit from grounded battery through the filament of lamp 56, middle armature and back contact of relay 33, con-

ductor 57, armature and back contact of relay 58, conductor 75 to ground, through the inner lower armature and front contact of relay 21. Upon noting the lamp signals, the operator, realizing the conversation has ended, takes down the connection and restores the apparatus to normal.

If at any time during the signaling of the called party the calling subscriber should 10 abandon the call, relays 13 and 17 are de-energized as heretofore described and relay 17 establishes at its inner upper armature and back contact a circuit for relay 14 which may be traced from grounded battery 15 through the winding of relay 14, conductor 54, inner upper armature and back contact of relay 17, and conductor 59, to ground, through the inner lower armature and front contact of relay 21, this relay being ener- 20 gized at this time owing to the insertion of plug 24 into jack 25. Relay 14 at its upper- most armature and back contact interrupts the ringing current circuit from the source at Y or Z whichever may be employed at the 25 time. It is therefore, evident that if during the period of ringing a called subscriber, the calling subscriber should abandon the call, the ringing current is automatically disconnected from the line by the operation of re- 30 lay 14.

Having described in detail the establishment of a connection between the subscriber at station A and a subscriber on line B, it will now be assumed that this connection 35 still exists or is in the process of completion and that a second operator at a position at which lamp 9 is located attempts to handle the call upon noting the illumination of lamp 9. It is to be understood that the operator 40 at such position attempts to handle the incoming call immediately after the first operator has answered the call, otherwise the lamp 9 would have been extinguished upon the insertion of plug 11 into jack 12.

The second operator having a cord identical with the one shown in the drawing, inserts the plug 11 into jack 50, the sleeve of 45 jack 50 being multipled with that of jack 12 now has a busy potential thereon owing to the insertion of plug 11 of the original cord into jack 12 by the first operator. The potential on the sleeve of jack 12 has been provided from the battery 51 associated with the sleeve conductor 52. Therefore, upon inserting plug 11 of the second cord into jack 50, an energizing circuit is established for discriminating relay 16 extending from the busy potential on the sleeve of jack 50, through elements of the second cord circuit 55 including the sleeve contacts of plug 11, sleeve conductor 52, armature and back contact of relay 13, winding of relay 16, conductor 53, inner lower armature and back contact of relay 17, and conductor 23 to ground, through the inner lower armature

and back contact of relay 21. Relay 16, in operating, establishes an energizing circuit for a relay 14 extending from grounded battery, through the winding of relay 14, conductor 54, and thence to ground, through the 70 armature and front contact of relay 16. Relay 14, in operating, disconnects talking battery and ground from the center of repeating coil 15, thus preventing the operation of the supervisory relay 13 and the associated 75 sleeve relay 17. Since relay 17 does not operate the connection of the second operator's telephone set with the talking conductors of cord circuit is prevented. Relay 16, in operating, establishes energizing circuits 80 for supervisory lamps 55 and 56. The circuit for lamp 55 may be traced from grounded battery through the filament of lamp 55, thence to ground over the armature and front contact of relay 16. The circuit for lamp 56 may be traced from grounded battery through the filament of lamp 56, inner lower armature and back contact of relay 33, conductor 57, armature and back contact of relay 58, conductor 59, inner upper armature and back contact of relay 17 and thence to ground over the armature and front contacts of relay 16. It will be noted that relay 13 is made slow to operate in order to prevent its operation over the circuit 90 completed therefor including the subscriber's loop when plug 11 is inserted into jack 50. In order to indicate that it is slow to operate it is shown on the drawing with an arrow 95 intercepting its armature and pointing in the direction in which it moves slowly.

It is evident from the foregoing description that a second operator cannot handle a call that is being attended to by another operator and if she should attempt to do so, she is sufficiently warned of the busy condition of the line not only by the illumination of lamps 55 and 56 but also by the absence of line noises in her head set which is sufficient to inform her that her set has not been connected to the talking conductors of the calling line.

Referring now to Fig. 2, the method of establishing a connection between subscriber A' and subscribers on lines B' is as follows:

Upon removing the receiver from the switchhook, the subscriber at station A' effects a circuit for line relay 100 which may be traced from grounded battery through the right-hand winding of relay 100, inner armature and back contact of cut-off relay 101, line conductor 102, over the subscriber's line loop, line conductor 103, outer armature and back contact of relay 101, and thence to ground through the left-hand winding of relay 100. Line relay 100 thereupon energizes and at its armature and front contact establishes obvious circuits for the line lamps 104, 105 and 106. As in the preceding case, these lamps are located at different operators' po- 120 125 130

sitions in a central office. Upon noting the illumination of the lamps any one of the operators may answer the call. It will be assumed here that the operator before the 5 position designated by the lamp 106 is the first to attempt to handle the call.

The operator inserts plug 107 into jack 103 and, in so doing, establishes an energizing circuit for slow to operate supervisory relay 109 which may be traced from grounded battery through the uppermost armature and back contact of relay 110, lower left-hand winding of repeating coil 111, winding of relay 109, ring conductor of the cord circuit C', ring contacts of plug 107 and jack 108, over the subscriber's line loop, tip contacts of jack 108 and plug 107, tip conductor of the cord circuit C', upper left-hand winding of repeating coil 111, and thence to 20 ground through the lowermost armature and back contact of relay 110. Relay 109, in operating, removes the discriminating test relay 112 from the sleeve of the cord and substitutes therefor the regular sleeve relay 25 113 which thereupon energizes over a circuit extending from grounded battery through the winding of relay 113, sleeve conductor 114, armature and front contact of relay 109, sleeve contacts of plug 107 and jack 108, 30 sleeve conductor 115, and thence to ground through the winding of cut-off relay 101. Relays 101 and 113 energize in the circuit just traced. Relay 101, in operating, disconnects the line relay 100 from the subscriber's 35 line conductors which relay thereupon releases and opens the circuit for lamps 104, 105 and 106 which are thereby extinguished. Relay 113, in operating, connects at its inner upper and innermost upper armatures 40 and front contacts, the operator's telephone set (not shown but designated by "OT") with the talking conductors of the cord circuit by way of the normal contacts of relay 120. At its lowermost armature and front 45 contact, relay 113 establishes an energizing circuit for the position register 116 which may be traced from grounded battery through the operating windings of register 116, conductor 117, lowest armature and front contact of relay 113, conductor 118, and thence to ground, through the armature and back contact of relay 119. The functions of the position register as stated hereinbefore are well known in the art and need 50 not be explained here. Relay 113 at its inner lower armature opens the circuit for supervisory lamp 123 to prevent its illumination at this time and also at its uppermost armature and front contact connects the busy test lead to the tip conductor of the calling end of the cord circuit.

The operator now converses with the calling subscriber and ascertains the nature of the call. Upon learning that a subscriber on line B' is desired, the operator inserts

the calling plug 121 of cord C' into jack 122 associated with the called subscriber's line.

Upon insertion of plug 121 into jack 122, a circuit is established extending from 70 grounded battery through the middle armature and back contact of relay 110, conductor 195, winding of relay 120, conductor 124, right-hand winding of relay 119, conductor 125, and sleeve contacts of plug 121 75 and jack 122 to ground through the winding of the cut-off relay associated with jack 122. An energizing circuit is also established for relay 119 extending from grounded battery through the left-hand winding of relay 119, 80 conductor 125, sleeve contacts of plug 121 and jack 122, and thence to ground through the winding of the cut-off relay associated with jack 122. Relays 120 and 119 energize in the circuits just traced. Relay 120 in 85 operating disconnects at its lowest and uppermost armatures and back contacts the operator's telephone set from the talking strands of the cord circuit and carries the talking strands to the contacts of relay 128. 90 Relay 119 interrupts the energizing circuit for position register 116 and at the same time establishes a circuit for relay 126 which may be traced from grounded battery through the winding of relay 126, conductor 95 127 and thence to ground over the armature and front contact of relay 119. Relay 126 thereupon energizes and at its upper armature and front contact makes the tip conductor of the cord circuit continuous and 100 disconnects the busy test lead 180 from the tip conductor of the cord. Relay 126 also establishes an energizing circuit for relay 128 which may be traced from grounded battery through the winding of relay 128, 105 left-hand armature and back contact of relay 142, conductor 143, armature and back contact of relay 134, conductor 144, and thence to ground, through the make contacts and lower armature of relay 126. Relay 128 in operating connects conductors 140 and 141 associated with the four-party ringing keys to the ring and tip conductors of the cord circuit. Relay 142 does not energize at this time owing to the shunt about 115 its winding which includes conductor 144, the armature of relay 134 and conductor 143. The connection is now fully established and the operator proceeds to ring the called-for subscriber in the following manner.

As in the preceding case, Fig. 2 discloses a four-party semi-selective ringing system and the manner in which the signaling apparatus at the different stations is operated is as follows:

It is to be understood that two parties are signaled on the ring conductor and two on the tip conductor, one of the parties on the ring conductor answering a two-ring signal and the other party answering a single ring 130

signal while one party on the tip conductor responds to a two-ring signal while the other replies to a single ring signal.

Relay 126 in operating, as heretofore described, establishes a circuit for relay 150 which is traced from grounded battery through the live segment and brush of pick-up interrupter X', when such interrupter is in its pick-up position, conductor 151, the 10 break contacts of relay 150, conductor 152, right-hand armature and back contact of relay 142, conductor 153, winding of relay 150, conductor 154, and thence to ground through the lower armature and front contact of relay 126. Relay 150, in operating, bridges the conductors 135 and 164 for a purpose hereinafter to be described and also establishes a locking circuit for itself which may be traced from grounded battery through 20 its right-hand armature and front contact, conductor 152, right-hand armature and back contact of relay 142, conductor 153, winding of relay 150, conductor 154, and thence to ground through the front contact 25 and lower armature of relay 126.

Assuming that the party W' is the desired subscriber, the operator actuates ringing key W¹⁹⁶ which places ground on the tip conductor of the line and also establishes a circuit extending from the grounded one-ring signaling current source at Z', over the live segment and brush of the interrupter at Z', conductor 161, left-hand armature and back contact of relay 133, winding of relay 134, 30 conductor 135, contacts 136 of key W¹⁹⁶, conductor 127, right-hand normally closed contacts of key R¹⁹⁷, conductor 138, right-hand normally closed contacts of key J¹⁹⁸, conductors 139 and 140, lowermost armature 35 and front contact of relay 128, ring contacts of plug 121 and jack 122, the ring conductor of the line B', and thence to ground through the operating windings of the bells at stations W' and R'. The bells are actuated 40 from a one-ring signaling source and since the party at W' only replies to a one-ring signal, the receiver thereat is removed. The party at R', replying only to a two-ring signal, does not heed the one-ring signal.

It will be assumed now that the party R' is desired and the operator actuates the key R¹⁹⁷. In so doing an energizing circuit for relay 133 is established, which may be traced from grounded battery through the right-hand armature and front contact of relay 150, conductor 152, right-hand armature and back contact of relay 142, conductor 153, winding of relay 133, conductors 162 and 160, and thence to ground through the left-hand contact of key R¹⁹⁷. Relay 133, in operating, disconnects the one-ring signal source from conductor 135 and substitutes therefor the two-ring signal source from interrupter Y'. Ringing current is then transmitted from the one-ring source at Y' over

conductor 132, the armatures and front contacts of relay 133, winding of relay 134, conductor 135, conductor 163, left-hand armature and front contact of relay 150, conductor 164, right-hand contacts of key R¹⁹⁷, conductor 138, normally closed right-hand contacts of key J¹⁹⁸, conductors 139 and 140, lowest armature and front contact of relay 128, ring contacts of plug 121 and jack 122, ring conductor of the line B' and thence to ground through the operating windings of the bells at R' and W'. Since the ringing current is transmitted from the two-ring signaling source at Y', the subscriber at R' only, responds to the signal. 80

If the party at J' is the required subscriber, the operator actuates key J¹⁹⁸, all other keys being released and relay 133 being deenergized. Ground is thereby connected to the ring conductor of the cord circuit. 85 One-ring signaling current is then transmitted from the source at Z' over a circuit traced from this source and including conductor 161, left-hand armature and back contact of relay 133, winding of relay 134, conductors 135 and 163, left-hand armature and front contact of relay 150, conductor 164, left-hand contacts of key J¹⁹⁸, right-hand normally closed contacts of key M¹⁹⁹, conductor 166, left-hand normally closed contacts of key W¹⁹⁶, conductors 142 and 141, middle armature and front contact of relay 128, upper armature and front contact of relay 126, tip contacts of plug 121 and jack 122, over the tip conductor of the line B' and thence to ground, through the operating windings of the bells of stations J' and M'. The subscriber at J' hearing the one-ring signal answers the call whereas the subscriber at M' does not heed the signal. 100

If the subscriber at M' is desired the operator actuates key M¹⁹⁹ and establishes a circuit for relay 133, as described in connection with the actuation of key R¹⁹⁷. This relay substitutes the two-ring signaling source at Y' for the one-ring signaling source normally associated with the conductor 135. One-ring signaling current is thereupon transmitted over the tip conductor of the line to actuate the bells at stations M' and J'. The subscriber at J' does not reply to the two-ring signal, whereas the party at M' does. 110

The desired party, upon hearing the signal, removes the receiver from the switchhook and in so doing increases the current in the circuit including relay 134 to such an extent that this relay operates and at its armature and back contact removes the shunt around the winding of relay 142. Relay 142 thereupon operates and connects battery directly with the winding of relay 128 thereby neutralizing the effect of the battery normally associated with this wind- 120 125 130

ing. Relay 123 deenergizes thereby rendering the talking conductors of the cord circuit continuous.

In removing the receiver from the switchhook, a circuit is established for supervisory relay 127 which may be traced from grounded battery through the lower right-hand winding of repeating coil 111, winding of relay 127, lowermost armature and 5 front contact of relay 120, conductor 130, lowermost armature and back contact of relay 128, ring contacts of plug 121 and jack 122 over the subscriber's line loop, the tip contacts of jack 122 and plug 121, upper 10 15 armature and front contact of relay 126, middle armature and back contact of relay 128, conductor 129, uppermost armature and front contact of relay 120, and the upper right-hand winding of repeating coil 111 to 20 ground. Relay 127, in operating, opens the circuit for supervisory lamp 131 which otherwise would have been illuminated from the source associated with the upper armatures of relay 110 upon the release of relay 128.

It is to be noted that no signal is given the operator to inform her when the called subscriber has responded.

When the conversation has ended, the 30 calling subscriber replaces the receiver on the switchhook thereby releasing supervisory relay 109. Relay 109 in deenergizing interrupts the circuit for relay 113 which, in releasing, closes a circuit from grounded 35 battery, through the filament of lamp 123, lower inner armature and back contact of relay 113 to ground, through the armature and front contact of relay 119. Lamp 123 is illuminated in this circuit and informs the 40 operator that the calling subscriber has terminated the conversation and has replaced the receiver on the switchhook.

When the called subscriber replaces the receiver on the switchhook, supervisory relay 127 is deenergized whereupon a circuit is established from grounded battery through the middle armature and back contact of relay 110, conductor 195, middle armature and front contact of relay 120, armature and back contact of relay 127, conductor 190, uppermost armature and back contact of relay 128, and thence to ground 45 through the filament of supervisory lamp 131. Lamp 131 is illuminated in this circuit and notifies the operator that the called subscriber has replaced the receiver on the hook and the operator thereupon proceeds to take down the connection.

As in the description of the system shown 60 in Fig. 1, should an operator attempt to plug into a busy line, the discriminating test relay 112 would operate from the busy potential on the sleeve of the jack through the sleeve of the plug to ground at the armature and normal contact of relay 119. Re-

lay 112, in operating, establishes an obvious circuit for relay 110 which disconnects ground and battery from the tip and ring conductors respectively of the answering end of the cord circuit. The regular sleeve 70 relay 113 is prevented from operating, since slow to operate supervisory relay 109 does not operate, thereby preventing the operator's telephone set from being automatically connected to the talking conductors of the 75 cord circuit. Supervisory lamps 131 and 123 at the calling and answering ends of the cord circuit are illuminated, lamp 131 over a circuit traced from grounded battery through the middle armature and front contact of relay 110, conductor 191, middle armature and back contact of relay 120, armature and contact of relay 127, conductor 190, uppermost armature and back contact of relay 128 and to ground through the 80 filament of lamp 131. Lamp 123 is illuminated over a circuit extending from grounded battery through the filament of lamp 123, thence to ground over the armature and front contact of relay 112.

It is evident from the foregoing description that the second operator is sufficiently warned when she attempts to plug into a busy line as well as is actually prevented from interfering with the establishment of 95 the connection by the first operator.

What is claimed is:

1. In a telephone system, a calling line, operators' link circuits comprising a pair of talking conductors and a third conductor, 100 a source of current for said link circuits, and means controlled over said third conductor for disconnecting said source of current from one of said link circuits when more than one of said link circuits are connected to said calling line.

2. In a telephone system, a calling line, a link circuit comprising a pair of talking conductors and a third conductor, a source of current for said link circuit, a slow operating relay included in one of said talking conductors and means normally associated with the third conductor of said link circuit for disconnecting said source of current from said link circuit, said means being under the control of said slow operating relay.

3. In a telephone system, a calling line, link circuits comprising a pair of talking conductors and a third conductor, a current 120 source in each of said link circuits, an operator's telephone for said link circuits, a plurality of signals for each of said link circuits and means included in said third conductor responsive to the association of 125 more than one of said link circuits with said calling line, whereby said current source is disconnected from its associated link circuit, said operator's telephone is prevented from association with its respective 130

link circuit and said signals are operated.

4. In a telephone system, telephone lines, each having a plurality of connecting terminals, link circuits each comprising a pair of talking conductors and a third conductor terminating in manually operable terminals for connection with said line terminals, a signal at each terminal of said link circuit and means included in said third conductor for effecting the operation of the signal at each end of said link circuit upon the association of more than one of said link circuits with one of said lines.

5. In a telephone system, a telephone line, terminating at a plurality of positions at a switchboard, a plurality of link circuits at each of said positions for answering calls for said lines, each of said link circuits comprising a pair of talking conductors and a third conductor, a slow operating relay included in one of the talking conductors in each of said link circuits and means included in the third conductor of each of said link circuits and controlled by said slow operating relay, for preventing the operative association of more than one of said link circuits with said telephone line.

6. In a telephone system, a busy telephone line, a link circuit having a calling and an answering plug, a calling supervisory signal associated with said calling plug, an answering supervisory signal associated with said answering plug, and means responsive to the connection of said answering plug of said link circuit to said busy telephone line for operating both said signals.

7. In a telephone system, a calling line, operators' link circuits comprising a pair of talking conductors and a third conductor, a source of current normally associated with each of said link circuits, and means controlled over said third conductor for disconnecting said source of current from one of said link circuits when more than one of said link circuits are connected to said calling line.

8. In a telephone system, a calling line, a source of current, operator's link circuits each having an answering and a calling end, each of said link circuits comprising a pair of talking conductors and a third conductor and having the talking conductors of the answering end normally connected to said source of current, and each said link circuit having a relay normally associated with said third conductor effective upon its operation to open said normal connection between said talking conductors and said source of current, each of said relays being responsive to the connection of the answer-

ing end of its associated link circuit with said calling line except the first in point of time so connected.

9. In a telephone system, a calling line, operators' link circuits comprising a pair of talking conductors and a third conductor and having answering and calling plugs, a supervisory relay normally connected to the answering plugs of each of said link circuits, a source of current for each of said link circuits, and means associated with said third conductor and controlled by said supervisory relay for disconnecting said source of current from one of said link circuits when more than one of said link circuits are connected with said calling line.

10. In a telephone system, a calling line, operators' link circuits comprising two inductively coupled sections, each section having a pair of talking conductors and a third conductor, a source of current normally associated with one of said sections, and means associated with said third conductor and operating only upon association of more than one of said link circuits with said calling line for disconnecting said source of current from said section.

11. In a telephone system, a calling line, operators' link circuits having answering and calling plugs and comprising a pair of talking conductors and a third conductor, an operator's telephone set for association with said link circuits, means including a slow-operating relay connected to the talking conductor of the answering plug of each of said link circuits, for connecting the operator's telephone set to a corresponding link circuit, and means including a second relay normally connected to said third conductor for controlling said slow-operating relay for preventing the association of said telephone set with other link circuits when more than one of said link circuits are connected to said calling line.

12. In a telephone system, a calling line, link circuits having answering and calling plugs and each comprising a pair of talking conductors and a third conductor, a signaling device for each of said plugs, a slow acting relay in the circuit of one of said talking conductors, and means normally associated with the third conductor of said link circuits and controlled by said slow-operating relay for causing the signaling devices of one of said link circuits to be operated when more than one of said link circuits are connected with said calling line.

In testimony whereof, I have signed my name to this specification this 9th day of October, 1922.

RAND S. BAILEY.
